ATTORNEYS

UNITED STATES PATENT OFFICE.

GEORGE KARP, OF LONG ISLAND CITY, NEW YORK.

CIGAR CONTAINER AND HUMIDOR.

Application filed June 17, 1922. Serial No. 569,170.

To all whom it may concern:

Be it known that I, GEORGE KARP, a citizen of the United States, and resident of Long Island City, in the county of Queens and State of New York, have invented certain new and useful Improvements in Cigar Containers and Humidors, of which the following is a specification.

The principal object of this invention is 10 to provide a novel and improved container or humidor for cigars and cigarettes.

A further object is to provide a device of this character with means to deliver a single cigar or cigarette as desired.

15 Another object is to provide means to lock the delivery means.

For the accomplishment of these and such further objects as will hereinafter be apparent to those skilled in the art to which 20 this appertains, the invention consists in the construction, combination and arrangement of parts herein specifically described and illustrated in the accompanying drawings, wherein is shown a preferred embodiment 25 of the invention, but it is to be understood that changes, variations and modifications may be resorted to which fall within the scope of the claim hereunto appended.

In the drawings forming a portion of this 30 specification

Fig. 1 is a transverse vertical section through a container embodying my invention.

Fig. 2 is a front elevation partly in section.

Fig. 3 is a section on the line 3—3 of Fig. 1.

As shown in the drawings, the container comprises the end walls 10 and 11, front and rear walls 12 and 13 respectively and top 40 members 14 and 15.

The front and rear walls terminate a short distance above the base members 16 to provide transverse slots 17 through which slidably project the receptacles 18 and 18^a.

45 A base block 19 is secured centrally of the bottom of the container and is provided with a central upwardly projecting rib 20 which serves to limit the inward movement of the receptacles, and also acts as an abutment for the springs 21 which are mounted within recesses 22 provided in the inner face of the receptacles 18 and 18^a. Secured to the under faces of each of the receptacles is a keeper 23, which is adapted to be engaged by a catch 24 pivoted as at 25 to the block 19. A coiled spring 26 is provided

to normally hold the catch 24 in engagement with the keeper 23 and an actuating rod 27 is pivoted to each catch and extends outwardly through the base member 16, the base members being preferably provided with a metal thimble or sleeve 28 through which the rod 27 slides freely. One of the receptacles 18 is provided in its upper face with a cigar receiving groove 29 which is 60 so located that its outer edge will be substantially in alignment with the inner face of the adjacent wall of the container when the receptacle is held in its inner position by the catch 24 as shown in full lines in 70 Fig. 1. The inner faces of the grooves 29 and 29^a are rounded off as at 30 to eliminate any sharp edges which might tend to destroy the wrappers of the cigars or cigarettes. The receptacle 18^a is provided 75 in its upper face with a groove 29^a similar to the groove 29 but of smaller depth and width to receive a cigarette indicated by the numeral 50.

A guide block 31 of triangular transverse 80 cross section is mounted centrally of the container upon the rib 20 and extends from end to end of the device.

Secured to one of the upper faces of the block 31 adjacent the apex thereof is a 85 partition piece 41 which extends upwardly to form a continuation of the face 31^a of the guide block and serves to divide the container into the compartments A and B. The compartment A being intended for the 90 reception of cigars and compartment B for cigarettes. Due to the difference in length between the cigars and cigarettes, it is therefore desirable to place a partition 42 shown in Fig. 3 extending at right angles to the 95 partition 41 and serving to keep the cigarettes in neatly stacked condition. I have also found it desirable to insert a guiding piece 43 extending from the upper end of the partition 41 downwardly into the compartment B. This guiding piece assists in causing cigarettes to be maintained in proper horizontal alignment with the cigarette receiving groove 29^a.

Means are provided to lock the receptacles 105 when desired and comprise a locking bar 32 for each of the receptacles, provided with an elongated slot 33, through which the headed screw 33^a passes, the screw 33^a being secured in the sidewall 10. An actuating 110 rod 34 is pivoted to the upper end of the locking bar 32, both of the actuating rods

being pivoted as at 40 to the side wall. Each of the receptacles are provided with a recess 35 in which the lower end of the locking bar is adapted to be engaged to lock the receptacles against outward movement.

The top member 14 is hinged as at 36 to the top member 15 and a lock 37 is provided to securely lock the top of the container. Humidor pads 38 of the well known type comprising a sheet of blotting paper encased within a perforated aluminum sheet are preferably mounted on the inner faces of the top members.

15 The operation of the device is as follows:—

Assuming that a quantity of cigars or cigarettes have been placed within the container, they will normally tend to fall downwardly into the cigar and cigarette receiving grooves 29 and 29^a respectively, the surface 31^a of triangular shaped block 31 and partition 41 guiding the cigars accurately towards the groove 29 while the face 31^b will 25 guide the cigarettes toward the groove 29^a, it being understood that the receptacles 18 and 18^a are in the closed or inward position. If it is desired to obtain a cigar, the rod 27 for the receptacle 18 is pushed inwardly 30 releasing the catch 24 from engagement with the keeper 23, and permitting the drawer 18 to move outwardly under the influence of the spring 21. A cigarette may obviously be obtained in a like manner by operating the 35 rod for the receptacle 18^a.

When it is desired to prevent anyone from appropriating the cigars or cigarettes in the absence of the owner, the receptacles 18 and 18^a may be locked in closed position by opening the top piece 14, and actuating the rods 34 to cause the lower ends of the locking bars 32 to be engaged within the recesses 35, after which the top 14 is closed and locked by the lock 37 which may be of any 45 suitable construction. It will be obvious that with the construction of the locking means disclosed either or both the receptacles may be locked as desired.

It will be noted that the keepers 23 also 50 serve to act as a stop to limit the outward

movement of the receptacles, the keeper abutting the inner face of the base block 16 as shown by the dotted line position of the receptacle 18^a in Fig. 1.

It will be apparent that the device may be 55 used for cigars or cigarettes alone and that both of the receptacles may be constructed with similar grooves, the dimensions of which will depend upon whether the container is to be used only for cigars or only 60 for cigarettes.

Having thus described my invention, what I claim as new and desire to secure by Letters Patent, is:

A container adapted to hold a plurality of 65 articles such as cigars, cigarettes or the like, means to divide said container into a pair of compartments, a receptacle for each compartment slidably mounted within said container and having a transverse groove there- 70 in adapted to contain only a single article, said means being constructed and arranged to cause the articles to be guided downwardly in opposite directions towards and in alignment with the respective groove for 75 each compartment, resilient means for normally urging each receptacle outwardly of said container and means to hold each receptacle within said container against the action of said resilient means, comprising a 80 keeper mounted on each of said receptacles, a pivoted catch having a hooked end to engage said keeper and a rod pivotally connected to said catch extending outwardly of 85 said container, means independent of said catch and rod to engage said receptacles and retain same within the container when said catch is released, said last mentioned means comprising a locking bar for each receptacle 90 slidably mounted on said container, and a manually operable rod pivoted to said locking bar and pivotally mounted on said container adapted to actuate said locking bar into or out of engagement with said receptacle. 95

Signed at New York, in the county of New York, and State of New York this 26 day of May, A. D. 1922.

GEORGE KARP.
